(57) **CLAIM**

The ornamental design for a light with faceted LED, as shown and described.

DESCRIPTION

FIG. 1 is a top and right perspective view of a light with faceted LED, showing my design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof; and,

FIG. 7 is a bottom plan view thereof.

The broken lines shown in the drawings are included for the purpose of illustrating portions of the light with faceted LED that form no part of the claimed design.
